COMBINED COMB AND CLIPPERS

Filed Nov. 9, 1945

UNITED STATES PATENT OFFICE

2,465,694

COMBINED COMB AND CLIPPER

Wallace Lester Norwood, Santa Ynez, Calif.

Application November 9, 1945, Serial No. 627,658

1 Claim. (Cl. 30—209)

1

The present invention relates to new and useful improvements in tonsorial devices and more particularly to a combined comb and hair clippers.

An important object of the present invention is to provide a device of this character by means of which a person's hair may be cut without requiring the use of a comb held separately for lifting the hair away from the scalp of a person while cutting or trimming the same.

More specifically the invention embodies the provision of a comb including teeth and at one side of which a reciprocating cutter is operatively mounted and including cutting teeth adapted to work transversely at the inner ends of the teeth of the comb to perform a cutting action.

A still further object of the invention is to provide a device of this character which may be either electrically or manually operated and which at the same time is simple and practical in construction, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view showing the electrically operated clippers.

Figure 2 is a front elevational view thereof.

Figure 3 is a side elevational view of a modified form of reciprocating cutter.

Figure 4 is a fragmentary side elevational view of the clippers with the bolts shown in section and the leaf springs removed to show the slots behind the same.

Figure 5 is a transverse sectional view taken substantially on a line 5—5 of Figure 1, and

Figure 6 is a group perspective view of one of the connectors for slidably mounting the stationary and movable cutters.

Figure 7 is a fragmentary side elevational view of a manually operative handle for the clippers.

Referring now to the drawings in detail wherein for the purpose of illustration I have disclosed a preferred embodiment of the invention, the numeral 5 designates a stationary cutter which includes a rear edge 6 and teeth 7 projecting from the front edge thereof, the cutter 5 being constructed of a size and shape adapted for use as a comb.

To one side of the rear edge 6 of the stationary cutter is positioned the rear edge 8 of a movable

2

cutter which includes relatively short teeth 9 projecting from its front edge and arranged in cutting relation with respect to the inner ends of the teeth 7.

5 The rear edge of the movable cutter is provided with a plurality of longitudinally extending slots 10 within which guide blocks 11 are slidably mounted, the blocks being positioned on the smooth portion 12 of a bolt 13 which is threaded into the rear portion 6 of the stationary cutter 5.

Positioned under the head 14 of the bolt 13 is a leaf spring 15 adapted to bear against the outer side of the movable cutter 8 to yieldably maintain the cutters in close cooperating cutting relation.

15 The inner end of the stationary cutter 5 is formed with a shank 16 provided at its rear end with a handle 17 which may constitute a housing for an electric motor including a pitman mechanism (not shown) of conventional construction 20 for operating a pitman rod 18 which is pivotally connected at its front end as at 19 to the movable cutter 8.

In the modification shown in Figure 3, the teeth 25 of the movable cutter 24 are of dovetailed form. 25 Otherwise the construction is the same as that already described.

Also if desired the shank 16 of the stationary cutter 5 may be constructed with a handle of a type shown at 20 in Figure 7 of the drawings and 30 including a pivoted lever 21 connected to the movable cutter by means of a link 22 for reciprocably actuating the movable cutter. A leaf spring 23 is positioned between the lever 21 and handle 20 to move the lever in one direction while a squeezing action by the hand of a person will move the lever in its opposite direction.

It is believed the construction and manner of operation of the device will be apparent from the foregoing, the teeth 7 of the stationary cutter 40 5 being used to engage the hair of a person while the movable cutter 8 is reciprocated to cut or trim the hair.

In view of the foregoing description taken in conjunction with the accompanying drawings it 45 is believed that a clear understanding of the construction, operation and advantages of the device will be quite apparent to those skilled in this art. A more detailed description is accordingly deemed unnecessary.

50 It is to be understood, however, that even though there is herein shown and described a preferred embodiment of the invention the same is susceptible to certain changes fully comprehended by the spirit of the invention as herein

described and the scope of the appended claim.
What is claimed is:

A combined comb and clippers comprising a stationary cutter having comb teeth at one edge thereof, a movable cutter having relatively short teeth positioned at one side of the comb teeth in cutting relation therewith, said movable cutter having longitudinal slots, a guide block positioned in each slot to provide a slideable mounting for the movable cutter, a bolt inserted through and fitted in the block and anchored in the stationary cutter, and a leaf spring between the head of the bolt and the guide block and covering the slot.

WALLACE LESTER NORWOOD.
